UNITED STATES PATENT OFFICE

2,136,246

LAMP HOLDER

Henry H. Helmbright, Cleveland Heights, Ohio,
assignor to General Electric Company, a corporation of New York

Application March 12, 1937, Serial No. 130,467

4 Claims. (Cl. 173—328)

The present invention relates to lamp holders or sockets for cylindrical lamps having a contact ferrule at each end with which the lamp filament is connected and through which current is carried to the filament.

One object of the invention is to provide an improved socket or holder wherein the circuit through the lamp is not closed until the lamp is entirely in the sockets.

A further object of the invention is to provide a lamp holder wherein the supporting or holding means for the lamp is independent of the contact means.

A further object of the invention is to provide a lamp holder wherein the live part of the holder is well concealed and does not present an exposed contact which is likely to be inadvertently touched when a lamp is not in the holder.

For a consideration of what I believe to be novel and my invention, attention is directed to the following specification and the claims appended thereto.

In the drawing, Fig. 1 is an end view of a lamp holder embodying my invention; Fig. 2 is a sectional view taken on line 2—2 of Fig. 1 and showing on one side a cylindrical lamp in position in the socket, and Fig. 3 is a view showing another form of the socket.

Referring to the drawing, 1 indicates a cylindrical lamp having a contact ferrule 2 at each end to which the filament 3 is connected. It will be understood that lamps of this type are supported between two lamp holders, one at each end of the lamp and that one side of the circuit is connected to each holder. Figs. 1 and 2 show a double lamp holder, i. e., a lamp holder adapted to receive the ends of two adjacent lamps when two or more lamps are arranged in a row. Fig. 3 shows a single lamp holder, i. e., a lamp holder which receives the end of a single lamp. In the use of lamp holders, if a single lamp is to be supported then lamp holders, as shown in Fig. 3, are arranged one for each end of the lamp. If several lamps are to be supported in a row, then single lamp holders, as shown in Fig. 3, are mounted at the two ends while a double lamp holder, as shown in Figs. 1 and 2, is mounted at intermediate points between the lamps.

Referring to Figs. 1 and 2, 4 indicates a base of insulating material having wings 5 by means of which it may be mounted on a suitable support, the wings being provided with openings (not shown) to receive fastening screws. In opposite faces of base 4 are recesses 6 which are open at the top through radially extending passages as

indicated at 7. This leaves a vertical partition or wall 8 of insulating material between the two recesses. At the inner end of wall 8 and embedded therein is a metallic contact 9 to which is connected a binding post 10 having nuts 11 on its lower end by means of which a conductor wire may be connected to the binding post. Fastened on one side of wall 8 by rivets 12 is a spring holder or head 13 adapted to be engaged by the ferrule 2 on the end of lamp 1, the ferrule being provided with a recess 14 which fits over the head 13. On the other side of wall 8 is a second spring head 15 fastened in place by rivets 16. Head 15 is similar to head 13 and is adapted in the same way to engage with the ferrule on the end of a lamp. Fastened at the inner end of recesses 6 adjacent to contact 9 are spring contact fingers 17 held in place by suitable pins 18. Spring contact fingers 17 are biased by their inherent resiliency to a position normally out of engagement with contact 9, occupying the position shown for spring contact fingers 17 at the left hand side of Fig. 2. When a lamp is in place in the socket, its ferrule engages the spring contact finger 17 and forces it into engagement with contact 9 as shown at the right hand side of Fig. 2.

In Fig. 3 is shown a holder construction similar to that shown in Fig. 2 except that it is a single holder instead of a double holder and the same reference characters with the exponent "a" added have been applied to corresponding parts. The arrangement of the construction shown in Fig. 3 will be obvious from the description already given.

If found desirable, I may provide a cover 19 of suitable construction for closing the opening 7 through which the lamp ends are inserted into the recesses 6. In the present instance, I have shown a cover 19 comprising a curved member suitably pivoted to base 4 as is indicated at 20.

In the use of the invention, the sockets are mounted a distance apart to receive the two ends of a lamp between them. The lamp is inserted by opening the covers 19 and pushing the lamp into place between adjacent spring holders, the ends of the lamp entering through the radially extending passages 7. As the lamp approaches its final position, the lower portions of the ferrules 2 engage the spring contact fingers 17 and in its final position forces the spring contact fingers into engagement with the contacts 9, thus completing connection of the lamp filament to contacts 9. As the lamp moves into position, it compresses the heads 15 toward the walls 8 and in the final position the heads rest in the 35 40 45 50 55

recesses 14 in the ferrules at the two ends of the lamp, holding the lamp resiliently between them.

With this arrangement, it will be seen that the lamp must be entirely in place before the 5 circuit through the filament is closed. Also, it will be seen that if the lamp is inserted angularly into one socket and then inserted into the other socket by a pivotal movement, the filament will not be connected to the contact 9 of the first 10 socket until the lamp has been turned far enough to bring it almost completely into position in the second socket. Thus, the ferrule at the other end of the lamp would not be alive through the filament with the lamp only partially inserted 15 in the first socket.

In accordance with the provisions of the patent statutes, I have described the principle of operation of my invention together with one form of apparatus for carrying it out. It is to be understood, however, that the structure illustrated 20 is only by way of example and that the invention is only by way of example and that the invention may be carried out by other means.

What I claim as new and desire to secure by Letters Patent of the United States is:

25 1. In a lamp holder for a cylindrical lamp having a ferrule at its end, the combination of a base of insulating material having a recess in one face and a radially extending opening leading to the recess through which the end of a lamp may 30 be entered into the recess, a contact at the inner end of the recess, a spring member adapted to be moved into engagement with the contact by the insertion of a lamp into the holder, and a spring means in the recess for engagement with the 35 ferrule at the end of a lamp to hold it in position.

2. In a lamp holder for a cylindrical lamp having a ferrule at its end, the combination of a base 40 of insulating material having a recess in one face and a radially extending opening leading to the recess through which the end of a lamp may be entered into the recess, a contact embedded in the base at the inner end of the recess, a spring finger adjacent said contact, biased to a

position out of contact therewith, and adapted to be moved into engagement with the contact when a lamp is fully inserted into the holder, and a spring blade mounted on said base, said blade being compressed toward said base by engagement with the ferrule of said lamp to support the end of the lamp in said holder.

3. In a lamp holder for a cylindrical lamp having a ferrule at its end, the combination of a base of insulating material having a recess in one 1 face and a radially extending opening, leading to the recess through which the end of a lamp may be entered into the recess, a contact embedded in the base at the inner end of the recess, a spring finger adjacent said contact and 15 normally biased to a position out of contact therewith, a spring blade mounted on said base above said finger, said spring blade being flexed toward said base by engagement with the ferrule of said lamp to support the end of the lamp in 20 said holder, and said finger being simultaneously moved into engagement with said contact by said ferrule, and a removable cover closing said radial opening.

4. In a lamp holder for a plurality of cylindrical lamps having ferrules at their ends, the combination of a base of insulating material having recesses in opposite faces thereof, said recesses being separated by a wall, a contact embedded in the wall and being exposed at opposite 3 ends to each of said recesses, a spring finger disposed in each of said recesses and normally biased to a position out of engagement with a corresponding end of said contact, a spring blade mounted on each side of said wall in each of said 35 recesses, said spring blades being flexed toward the wall by engagement with the ferrules of separate lamps to support the corresponding end of the lamp in said holder and said fingers being moved simultaneously into engagement with the opposite ends of said contact by engagement with said ferrules whereby the ends of said lamps are electrically connected to said contact.

HENRY H. HELMCKRIGHT.
